UNITED STATES PATENT OFFICE.

STANISLAUS H. SAUVÉ, OF DENVER, COLORADO.

ELECTROMAGNETIC SIGNALING INSTRUMENT.

1,009,345.

Specification of Letters Patent. Patented Nov. 21, 1911.

Application filed June 18, 1910. Serial No. 567,721.

To all whom it may concern:

Be it known that I, STANISLAUS H. SAUVÉ, of Denver, in the county of Denver and State of Colorado, have invented certain new and useful Improvements in Electromagnetic Signaling Instruments; and I do hereby declare the following to be a full, clear, and exact description of the invention, such as will enable others skilled in the art to which it appertains to make and use the same.

The primary object of this invention is to provide simple and highly efficient means for producing sounds and making contacts in electro-magnetic instruments; and to facilitate and cheapen the cost of manufacture of the latter, as well as to reduce to a minimum the parts thereof.

The invention will be hereinafter fully set forth and particularly pointed out in the claims.

In the accompanying drawings, Figure 1 is a vertical longitudinal sectional view showing the coil of a telegraphic instrument equipped according to my invention. Figs. 2 and 3 show slight modifications. Fig. 4 shows my improvement applied to a bell, parts being in section. Fig. 5 shows a different arrangement as applied to a double bell. Fig. 6 is a section on line 6--6, Fig. 5. Fig. 7 is a modification. Fig. 8 is a diaphragmatic view of a buzzer arrangement.

Broadly speaking, my invention comprehends a loose, detached, freely-movable armature, preferably in the form of a ball, and capable of being quickly moved and caused to vibrate under electrical excitement produced in a local circuit. The manner in which the armature is arranged within, or relatively to, a coil may be varied, and different means may be employed for insuring the vibration of the armature in making and breaking contact. Likewise, various means may be employed for regulating the extent of the armature movement.

My invention will be first described in connection with telegraphic instruments.

In Fig. 1 I have shown a coil 1 into which is passed a post 2 of iron or steel, such post extending approximately half way in the coil at the center thereof. This post at its inner end has a plug 3 of non-magnetic ma-

terial, and at its outer end it is shown as connected by an adjusting screw 4 to a fixed frame. Extending upwardly within the coil, to a point near the lower end of post 2, is a magnet 5, which is shown in the form of a split tube having the properties of a horseshoe magnet. Centrally within this magnet is a non-magnetic stop or support, which is shown in the form of an adjustable screw 6 having a disk 7 on its inner end, its headed end being projected beyond the coil to enable the screw to be readily and easily adjusted so as to regulate the distance between its disk 7 and the end of post 2. 8 is a loose, detached, freely movable armature, which is shown in the form of a ball located within the open end of the magnet and normally resting against the disk 7. 70 Wires, as 9 and 10, lead from a local battery and are connected, respectively, to screws 4 and 6. Upon the closing of the current in the coil the ball armature 8 will adhere to the sides of the magnet 5 and strike upwardly against the non-magnetic plug 3, closing the local circuit through post 2. Upon the release of the current in the coil the ball armature will be released and by dropping will break the local circuit. This ball is perfectly free to move immediately upon the creation or cessation of the electrical excitement, and not being connected to any part is not liable to get out of order. By striking against the non-magnetic plug 85 3 the desired sound will be produced within the coil.

While I prefer to employ the adjustable stop or support for the ball armature, yet this is not absolutely essential, nor is it necessary, for all purposes, that the magnet be employed. In Fig. 2 I have shown the magnet omitted, and have indicated the support 6 as of non-magnetic material. If desired, however, the magnet may be employed in connection with a fixed non-magnetic post 12, as shown in Fig. 3, the magnet being marked 5*. If this arrangement is used as a relay, it may be wired so that the ball will constitute one terminal and the bell the other terminal of a local circuit.

In Fig. 4 I have shown my improvement in connection with a signaling bell 13, and in this connection I may employ a second

ball armature 14 located within the coil adjacent to the closed end of the magnet 5. Under electrical excitement the ball armature 8^a, and the second armature 14, will be moved in the same direction, and under the make and break action will alternately strike the bell 13 at diametrically opposite points, thus producing a clear and almost constant sound.

10 In Fig. 5 I have illustrated the application of my invention to a double bell, the two bell parts being shown at 15 and 16. In connection with each bell part I employ a coil 17, and between the parts I locate a permanent magnet 18 in the upper end of which is the ball armature 8^b which is freely movable at right angles to the axis of the magnet so as to alternately strike the two parts of the bell. I have shown the permanent magnet as having an opening formed therein to accommodate the ball, but if preferred other suitable means may be employed for holding the ball in proper relation to the magnet and yet permit it to freely vibrate alternately between the two bells.

In Fig. 7 I have shown a retaining hood 20 for the ball.

In Fig. 8 I have shown diagrammatically the use of my present improvement in connection with a buzzer. The central post 25 is shown as composed of two pieces of metal separated from each other by insulation 26 and from the surrounding coil tube 27 by insulation 28. The two pieces of metal of the post are connected to the coil and the battery so that they will in fact be a part of the circuit when the ball rests upon them. The circuit is closed by a lever or button 29. A rapid vibratory motion of the ball armature between the post and the bell 30 will be had when the circuit is closed.

It will be understood that the make and break causing the electrical excitement for producing the rapid vibration of the ball armature may be effected by any convenient apparatus, such as telegraph keys, push-buttons, turn-keys, levers, etc.

The advantages of my invention will be readily appreciated by those skilled in the art. The ball armature is free, not being connected to any part of the apparatus, and hence is not only capable of being quickly moved, but there are no parts which may be weakened by constant usage. The ball armature strikes the part with which it co-acts with sufficient force to produce the desired sound.

While I have shown and described various means for the employment of my invention, it will be understood that the latter is not limited either in its use or application to any special form of signaling device.

I claim as my invention:

65 1. In an electro-magnetic signaling instru-

ment having an electric coil, a freely movable disconnected armature in the form of a ball, and a fixed part against which such ball armature is designed to strike under electric excitement.

70

2. In an electro-magnetic signaling instrument having an electric coil, a fixed post arranged centrally within the coil, a stop or support in axial line with such post, and a ball armature located between such stop and said post and designed to vibrate between them under electric excitement.

75

3. In an electro-magnetic instrument having an electric coil, a fixed post arranged centrally within the coil, a magnet in axial line with such post, a stop or support within such magnet, and a ball armature located within such magnet and between said stop and post.

80

4. In an electro-magnetic instrument having an electric coil, a fixed post arranged centrally within the coil, a magnet in axial line with such post, an adjustable stop or support within such magnet, and a freely-movable armature located within such magnet and between said stop and post.

85

5. In an electro-magnetic instrument having an electric coil, a fixed post arranged centrally within the coil, a magnet in axial line with such post, an adjustable stop or support within such magnet, and a ball armature located within such magnet and between said stop and post.

90

6. In an electro-magnetic instrument having an electric coil, a fixed post arranged centrally within the coil, a split tube, forming a magnet, in axial line with such post, a stop or support within such split tube, and a ball armature located within such tube and between such stop and post.

100

7. In an electro-magnetic instrument having an electric coil, a fixed post arranged centrally within the coil, a split tube, forming a magnet, in axial line with said post, an adjustable stop or support within such split tube, and a ball armature located within such split tube and between said stop and post.

110

8. In an electro-magnetic instrument having an electric coil, a fixed post arranged centrally within the coil, such post being of magnetic metal and having at its inner end a plug of non-magnetic material, a stop in line with such post, and a freely-movable armature located between such stop and post.

115

9. In an electro-magnetic instrument having an electric coil, a fixed post arranged centrally within the coil, such post being of magnetic metal and having at its inner end a plug of non-magnetic material, a stop in line with such post, and a ball armature located between such stop and post.

120

10. In an electro-magnetic instrument having an electric coil, a fixed post arranged centrally within the coil, such post being of

130

magnetic metal and having at its inner end a plug of non-magnetic material, a magnet in axial line with said post, a stop within such magnet, and a ball armature located 5 within such magnet and between such stop and post.

In testimony whereof, I have signed this

specification in the presence of two subscribing witnesses.

STANISLAUS H. SAUVÉ.
